UNITED STATES PATENT OFFICE.

WILLIAM ATKINSON, OF BOXFORD, MASSACHUSETTS, ASSIGNOR TO THE VACUUM COMPANY, OF SOMERVILLE, MASSACHUSETTS, A CORPORATION OF MASSACHUSETTS.

METHOD OF DRYING GOODS.

1,415,623.

Specification of Letters Patent. Patented May 9, 1922.

Application filed October 12, 1918. Serial No. 257,855.

To all whom it may concern:

Be it known that I, WILLIAM ATKINSON, of Boxford, in the county of Essex and State of Massachusetts, a citizen of the United States, have invented a new and useful Improvement in Methods of Drying Goods, of which the following is a specification.

In certain types of drying it has been considered necessary, where the goods contain much moisture, to provide a condenser between the drier and the vacuum pump which shall condense the moisture collected by the air in the process. This has resulted in considerable expense because of the amount of power used to run the pump to draw the air through the condenser. My method is an improvement upon methods heretofore used so far as I know, in that vapor laden air passes from the heating chamber to a condensing chamber where it drops its moisture and circulates back through the heater to repeat the operation, which is continued as below described, a tank being provided to drain off the water or other liquid of condensation. The use of a vacuum pump may thus be dispensed with except to draw the initial vacuum after which the drying and condensation proceeds without the aid of a pump as below described.

My invention will be understood by reference to the drawings, in which—

Figure 1 is a longitudinal section, and

Fig. 2 a cross section on line 2—2 of Fig. 1.

The apparatus is divided into two chambers, one a heating chamber and the other a condensing chamber, both forming part of the same structure. The heating chamber in the accompanying drawing is lettered A and the condensing chamber of substantially the same size is lettered B. Both chambers as shown are cylindrical in shape. One wall *a* of the chamber A is preferably of steel and is surrounded by a covering of heat-insulating material C which may be attached to it in any convenient manner. The outer end of this chamber is closed by a closure *a'* bolted to the wall *a* and it also is covered with heat-insulating material C so that substantially no heat can be lost from this chamber except perhaps at its forward end. Its

forward end during the heating operation is closed by a vertically movable bulkhead D which closes, when desired, the front end of the chamber A but not airtight. It runs 55 in vertical ways and may be raised and lowered as required to carry out my process in any desired way as will be understood by one skilled in the art. It has a small opening *d* preferably near its top connecting the two 60 chambers. Both chambers may be provided with tracks *A*¹ as shown in order that cars E loaded with the material E¹ to be dried may be run into the chambers.

At the rear or inner end of the chamber 65 A there is provided a heater F connected to a suitable steam supply and a fan or blower G, the whole arranged within a hood H open at the bottom as at *h* so that the fan G may draw air into the casing H from below and 70 blow it out through the coils F¹. The platforms to the cars are preferably constructed of suitable width as at *e* to form a partition across the chamber, thus making a duct *a*² below the cars and requiring the air which 75 is circulated by the fan to pass around the chamber in the direction of the arrows so as to establish constant circulation.

By means of this portion of my apparatus 80 the goods may be thoroughly heated at atmospheric pressure to any desired degree, the bulkhead D being in position to close the chamber A. When the material is thoroughly heated the door D separating the heating chamber from the condensing chamber B is raised. This chamber B is not insulated in any way and will of necessity therefore be much cooler than the chamber 85 A and consequently will condense any moisture which the air from the chamber A may bring into it. The outer end of this chamber B is closed airtight by the gate *b*, and from that end of the chamber leads a pipe J, which is connected with a vacuum pump 90 (not shown) and has a valve *j* by which it 95 may be closed. Connected to the lower end of the outer wall of the chamber B is a pipe *k* having in it a valve *k*¹, the pipe connecting the chamber B with a tank K. This tank has preferably an ordinary gauge *k*² by 100 which the depth of liquid of condensation in it may be seen. A pipe *k*³ and valve *k*⁴

serve to draw off the contents of the tank K when desired.

To carry out my method by the use of this apparatus the material is placed on the cars, 5 which preferably are run into and out of the cylinder for loading and unloading, and the bulkhead D is closed after the material is introduced into the chamber A so as to retain the heat in the chamber A. The fan 10 then being started up there will be a circulation of air in the direction indicated by the arrows through this chamber, which will gradually heat the goods to be dried. To make the heat penetrate the material, for ex- 15 ample a bale of cotton or the like, the vacuum pump having been started, a partial vacuum is drawn, say five inches, and then immediately let down to air pressure. This results in drawing out some of the moisture 20 from the bales, its place being taken by heated air when the vacuum is relieved. By doing this a number of times the material may be thoroughly heated to or above boiling at the vacuum it is planned to use in the 25 final condensation process.

When the goods are thoroughly heated the pressure in the chamber B is reduced below atmospheric pressure by the pump to say ten inches or whatever amount is desired 30 in the two chambers after the bulkhead D is raised to connect the chambers. The pump is then shut off by the valve *j* and the apparatus is left in that condition for such a time as experience has shown is desirable. The 35 process then goes on inside the tank, that is to say, the moisture in the goods boils out and the circulation of air containing the moisture is maintained by the fan G, which constantly forces air through the heater. 40 The bulkhead should then be opened wide or sufficiently to allow free circulation from one chamber to the other. The air is driven into the chamber B as shown by the dotted arrows where the moisture condenses because 45 the chamber B is not and has not been heated and will never get as hot as the chamber A. Circulation is constantly maintained by the fan and as the air and vapor pass into the chamber B and the vapor is condensed it is 50 collected in the tank K, the steam coil during this period being still maintained at its original or at any given desired temperature so as to ensure the maintaining of the temperature in the chamber A, the condensation 55 maintaining or increasing the vacuum in the chamber.

When it is determined that the material has been sufficiently dried air at atmospheric pressure is admitted and the gate *b* is opened 60 and the material removed the gate or bulkhead D being raised, if that has not already been done, or removed.

It is evident that this method may be carried out by other apparatus than that shown. 65 It employs features which I believe to be

new and has proved exceedingly useful and also economical for the reason that the pump is used but little in the process, thus saving power.

What I claim as my invention is:—

70

1. The method of drying above described which comprises passing a current of heated air at atmospheric pressure over the goods to be dried in a substantially closed chamber in which said air is confined until the goods 75 are thoroughly heated to a predetermined degree below the boiling point at atmospheric pressure, then so connecting the said chamber with a condensing chamber as to allow a free circulation of air between the two 80 chambers and reducing the pressure in the two chambers below atmospheric pressure, whereby the moisture in the goods will be vaporized and the air and vapor from said heated chamber will mingle with that in the 85 condensing chamber and the vapor will be condensed, and circulating the vapor-laden air in the two chambers whereby it will carry the moisture from the heating to the condensing chamber, deposit it there and return 90 to the heating chamber for further heating, absorbing and condensing.

2. The method of drying above described which consists in heating the goods to be dried to a predetermined temperature in a 95 closed chamber at atmospheric pressure, reducing the pressure in said chamber to such a point that the moisture in the goods will be vaporized and absorbed by the air in the chamber, causing the vapor-laden air to circulate and condensing the vapor therefrom and returning the air to the chamber to be reheated and to absorb other moisture from the goods and continuing the process until the goods are sufficiently dried.

105

3. That improvement in the art of drying which consists in circulating hot air around the material to be dried in a closed chamber until the goods are thoroughly heated to a high degree of temperature then reducing 110 the pressure to such a point that the moisture in the goods will be vaporized and absorbed by the air in the chamber and then condensing the vapor therefrom, and passing the dried air over the goods again whereby 115 the air will absorb other moisture from the goods, and continuing the process until the goods are sufficiently dried.

4. That method of drying goods which consists in placing the goods in a closed 120 chamber, heating the air therein at atmospheric pressure whereby the goods will be heated, reducing the air pressure and causing the air to circulate about the goods whereby the moisture will be withdrawn 122 from the goods, cooling the air to cause it to drop its moisture and reheating it whereby it will absorb more moisture from the goods and again cooling it and continuing the moisture-absorbing and dropping process 130

until the goods are substantially dried whereby the same air will be used throughout the drying process.

5. That method of drying goods under a partial vacuum in a closed chamber, which consists in alternately heating and cooling the air while under a pressure less than atmospheric pressure whereby the moisture

will be alternately withdrawn from the goods and taken up by the heated air, and 10 then condensed and the dried air reheated to take up more moisture from the goods, and the same air under a partial vacuum used constantly until the drying is complete.

WILLIAM ATKINSON.
